UNITED STATES PATENT OFFICE.

WILLIAM J. MARTIN, OF CLEVELAND, OHIO.

HORSESHOE QUOIT.

Application filed June 11, 1923. Serial No. 644,693.

To all whom it may concern:

Be it known that I, WILLIAM J. MARTIN, a citizen of the United States, residing at Cleveland, in the county of Cuyahoga and State of Ohio, have invented certain new and useful Improvements in Horseshoe Quoits, of which the following is a specification.

This invention relates to quoits of the horse shoe type, and has for its object to provide an improved quoit provided with means to prevent rebound of the same when it strikes the stake; also to provide an improved grip for the hand of the player and also to engage the ground when the quoit strikes. Further features of improvement will be apparent from the following description and the accompanying drawings.

In the drawings, Figure 1 is a plan of the quoit. Figure 2 is an end view. Fig. 3 is a side view.

Referring more specifically to the drawings, 6 indicates the body of the quoit, of general horse shoe shape. On one side or face adjacent the bend, it has a pair of calks 7 which are oppositely disposed with a recess 8 between the same affording a good grip for the hand of the player. The quoit also has calks 9 at the heels.

The inner edge of the quoit, adjacent the bend, has a pair of tapered recesses 9 with a tongue or point 10 between the same, and

these recesses serve the purpose of preventing rebound when the quoit hits the stake. That is to say, the recesses 9 are tapered to a size slightly smaller than the diameter of the stake indicated at 11, and when the quoit strikes the stake, the force of the impact will be lessened because it will be a glancing blow instead of a solid blow thereby preventing rebound of the quoit, and giving the player a better chance to increase the score when playing the game. The flattened and irregular shape of dual calks 7 will give a quite effective grip upon the ground when the calks strike and will serve to prevent sliding and irregular action.

I claim:

1. A horse-shoe quoit having a pair of calks on one face thereof, said calks comprising a curved rib extending along the bend of the shoe and having projections forming the calks and a recess therebetween adapted to receive the finger of the player.

2. A quoit, the inner edge of which is provided with a pair of tapered recesses with a pointed projection between them.

In testimony whereof, I affix my signature in presence of two witnesses.

WILLIAM J. MARTIN.

Witnesses:
